UNITED STATES PATENT OFFICE

2,069,770

TIE PULLER

Ernest C. Neal, Coquille, Oreg.

Application December 11, 1934, Serial No. 756,969

9 Claims. (Cl. 254—43)

The invention has for its primary purpose and object the removing of ties from placement in railway track.

The tie through the use of my new and improved device may be removed from the ballast with a minimum of disturbance to the ballast disposed adjacent to the tie.

The invention is comprised primarily of a frame that may be secured to the rail and the device is preferably placed between the end of the tie and the outside of the rail. Means is provided for engaging the base of the device with the rail and means is provided for effecting frictional driving relation between the device and 15 the top of the tie or between the device and the sides of the tie. After frictional contact has been effected with the tie the toothed cylinders that engage the surfaces of the tie are then rotated by the movement of a lever in either direction to thereby create longitudinal movement 20 of the tie and to pull the same from placement beneath the rails.

The object of my invention is to facilitate the removal of the tie from placement in a railway track with a minimum of disturbance to the ballast of the railway roadbed.

A further object of my invention consists in providing a simple means for the removal of the tie and to provide a device that may be utilized for this purpose by a single workman.

A still further object of my invention consists in so constructing the same that it will be comprised of a minimum number of parts and one that may be ruggedly made and one that will have a long and useful life with practical freedom from mechanical operating annoyances.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a perspective end view of a simplified embodiment of my device. In this view the rolls engage the top of the tie to be removed.

Fig. 2 is a side view of a modified form of the device. In this view the feed rollers are also adapted to engage the top of the tie.

Fig. 3 is a plan view of the mechanism illustrated in Fig. 2.

Fig. 4 is a sectional end view of the feeding pawls and ratchet wheels employed in the spe-

cies disclosed in Figs. 1 and 2. This view is taken on line 4—4 of Fig. 3, looking in the direction indicated.

Fig. 5 is an end view partly in section of a modified form of device. The device as illustrated here has feed rollers that engage the sides of the tie to be removed.

Fig. 6 is a plan view of the mechanism illustrated in Fig. 5.

Like reference characters refer to like parts throughout the several views.

Heretofore it has been the general custom, in the removal of the ties, to remove the ballast adjacent the tie both at the sides and at the bottom and to then replace the tie to be taken out, 15 with another tie, which required the replacing of the ballast and the reballasting and the retamping of the road bed at the point where the tie was taken out. This necessitated a retamping from time to time to compensate for the 20 compression that normally occurs upon road beds caused by trains passing along the track.

Through the use of my new and improved device the tie is pulled from place without disturbing the ballast adjacent the sides and at the bottom of the tie. This permits replacing the tie taken out with another with a minimum of disturbance of the ballast adjacent the tie.

My device is primarily comprised in its simplest embodiment of side plates 1 and 2. The side plates at the rail abutting ends have slits disposed therein that are positioned to engage the outer edge 3 of the base of the rail 4. A pair of arms 5 and 6 are hingedly secured to the side plates by any suitable hinging pins 7. The arms are secured together by a cross bar 8 and the side frame members are secured in spaced relation on their rail engaging ends by a cross plate 9 (Fig. 3). The rail engaging ends of the arms are fashioned to precisely fit and engage 40 the outer edge and the underside of the rail 10 of the rail. A tight working relation between the arms, the side frame members and the rail may be maintained by a tightening bolt 11 that passes through the cross bar 8 threaded and engages the base of the rail at 12 as shown in Figs. 1 and 2. By tightening the bolt 11 against the base of the rail it serves to press the arms 5, 6, firmly against the underside of the rail 10 of the rail. A cross shaft 13 is journaled upon its opposite ends in the side plates 1 and 2 and cylinders 14 and 15 are keyed to the shaft 13. Each of the cylinders has sharpened teeth disposed about its periphery to facilitate the frictional engagement of the cylinders with the top surface 16 55

of the tie 17. Locator plates 18 and 19 are disposed at the oppositely disposed sides of the side plates 1 and 2.

When the device has been precisely positioned upon the rail and the toothed cylinders are resting upon the tie the locator plates 18 and 19 are driven into the end of the tie with the fastening rivets 20 and 21 moving longitudinally of the side plates 1 and 2 in the slots 22 disposed within the side plates 1 and 2. This driving forces the inwardly extending sharpened ends 23 and 24 of the plates 18 and 19 into the end edge of the tie. As the tie is removed by the action of the toothed cylinder, the locator plates will be forced back to the outer end of the slots 22 and then will cut their way longitudinally along the edge of the tie.

The shaft 13 moves in an arcuate slot 25 disposed in the respective side plates 1 and 2 and the shaft extends outwardly from the outer surface of the side plates 1 and 2. Lugs 26 and 27 (Fig. 3) extend outwardly from the top of the side plates 1 and 2 and a tapering wedge 70 may then be driven between the outwardly extending ends of the shaft 13 and beneath the lugs 26 and 27 to thereby force contact between the sharpened teeth of the cylinders 14 and 15 and the top surface of the tie.

A ratchet wheel 28 is disposed between the cylinders 14 and 15 mounted upon the shaft 13 and the same is also keyed to the shaft 13 by a key 29, the shaft 13 being common also to the cylinders 14 and 15. An actuating lever 30 is rockably mounted upon a shaft 31. The shaft 31 is journaled upon its opposite ends within the respective side plates 1 and 2. Ratchet pawls 32 and 33 are secured to the lever 30 and engage the teeth of the ratchet wheel 28 to thereby actuate the toothed cylinders as the lever 30 is manually manipulated in either direction.

A slightly modified form of device may be made as illustrated in Figs. 2 and 3. When so made the side plates 1 and 2 are made to pass beneath the base 34 of the rail. An upwardly extending toe 35 is made to engage the inner edge 36 of the base of the rail. When placed in position as illustrated in Fig. 2, the cams 37 and 38 which are hinged to the respective side plates by suitable journal pins 39 and 40 have cam surfaces 41 that engage the opposite edge of the base of the rail. This precisely locates the assembly upon the rail which may then be tightened by the threaded member 11.

To facilitate the loosening of the cam relative to that of the base of the rail a lug 42 outwardly extends from each of the cams 37 and 38 beneath which any suitable bar or prying means may be placed to loosen the cam from the rail.

It may be found desirable to make a modified form of device as illustrated in Fig. 5 so that the cylinders 43 and 44 are made to engage the opposite sides 45 and 46 of the tie 47 that is to be removed. The cylinder 44 is fixedly disposed upon shaft 48 and the gear 49 is secured to the top end of the shaft 48. A shaft 50 is journaled in suitable bearings in the top side of the supporting frame 51 and a driving element 52 is secured to the shaft 50 and coacts with the gear 49. A sub-frame 53 coacts with the frame 51 and the toothed cylinder 43 is fixedly secured to a shaft 54 that is journaled relative to the sub-frame and a gear 55 is secured to the top end of the shaft 54. A driving element 56 coacts with the gear 55 and drives the same. The driving element 56 is mounted upon a shaft 57 and the shaft

57 is moveable telescopically of the hub 58. A bracket 59 upwardly extends from the primary frame 51 and a similar bracket 60 upwardly extends from the sub-frame assembly. The brackets 59 and 60 are spaced apart sufficiently to permit a reaction means 61 being placed therebetween to urge the cylinders 43 and 44 toward each other and to force intimate engagement of the same with the tie 47. Working relationship is maintained between the respective sub-frame and primary frame by a horizontal portion 62 of the sub-frame moving within any suitable guide 63. A ratchet wheel 64 is mounted upon the shaft 56 and the respective pawls 66 are manipulated by a lever 65 and the ratchet wheel associated therewith as heretofore described.

While the form of mechanism herein shown and described is admirably adapted to fulfill the objects primarily stated, it is to be understood that it is not intended to confine the invention to the embodiment herein shown and described, as it is susceptible of embodiment in various forms, all coming within the scope of the claims which follow.

I claim:

1. In a device of the class described, the combination of a pair of side plates secured in spaced relation by a cross plate, said side plates being shaped at one end to engage the bottom outside edge of the base of a railway rail, arms hingedly secured on their one end to the side plates and fashioned at their opposite end to engage the ball of the railway rail, adjustable means for forcibly engaging the side plates and the swinging arms with the railway rail, means slidably attached to the side plates for securing the device to the railway tie, cylinders having sharpened corrugations adjustably journaled between the side plates, the journaled shaft for the cylinders moving in an arcuate slot disposed in the side plates, means for forcibly moving the shaft in the arcuate slots and means for rotating the cylinders.

2. In a device of the class described, the combination of a frame, means for attaching the frame to a railway rail, a corrugated roller adjustably journaled within the frame, means for attaching the frame to the sides of a railway tie, means for forcibly engaging the roller with the top surface of the railway tie that is engaged by the frame, and means for rotating the roller.

3. In a device of the class described, the combination of a puller frame, means for fixedly attaching one end of the puller frame to a railway rail, means for securing the opposite end of the frame to a railway tie disposed beneath the rail, a pulling roller adjustably journaled within the frame, means for forcing engagement of the pulling roller with the tie and means for forcibly rotating the pulling roller.

4. In a device of the class described, in combination with a railway rail that is disposed in a railway track, comprising a puller frame, means for fixedly securing one end of the frame to a railway rail, means for attaching the frame to a railway tie disposed beneath the railway rail, a corrugated pulling roller adjustably journaled within the frame, means for forcibly engaging the roller with the top of the railway tie to which the frame is engaged and manipulative means for rotating the pulling roller.

5. In a device of the class described, in combination with a railway rail and tie, comprising a frame, means for fixedly securing the frame to the rail, means for securing the frame to the tie,

a pulling roller adjustably journaled within the frame, means for establishing pulling relation between the tie and the roller and means for rotating the roller.

5 6. A tie puller comprising a toothed roller adapted to engage and dig into the upper surface of a tie, means including a wedge for forcing engagement of the roller with the tie, and means including a ratchet wheel for bringing the 10 teeth successively into engagement with the tie.

10 7. A tie puller comprising a pair of aligned rollers provided with teeth adapted to engage and dig into the upper surface of a tie, and clamping means for forcing engagement of the roller with the tie, and ratchet mechanism mounted between said rollers for operating said rollers and thereby move the tie.

15 8. A tie puller comprising a plurality of rollers for frictionally engaging opposite sides of a tie, means for forcing intimate engagement of the rollers with the tie, and a ratchet mechanism including bevel gears operatively connected to each 5 of said rollers for operating the rollers and to thereby move the tie.

9. A tie puller comprising a frame having toothed means comprising a plurality of teeth adapted to engage and dig into the upper surface of the tie, means for bringing the teeth of said means successively into engagement with the tie, means adapted for mounting the puller with respect to the tie, and means to prevent relative vertical movement of the puller with 10 respect to the tie to prevent the puller from disengaging the tie during operation of the puller.

ERNEST C. NEAL.
